Primary Examiner — Kevin Rudzinski*Assistant Examiner* — Sean D Lough(74) *Attorney, Agent, or Firm* — Foley & Lardner LLP(57) **CLAIM**

We claim the ornamental design for a brake adjuster, as shown and described.

DESCRIPTION

FIG. 1 is a first perspective view of the claimed design;

FIG. 2 is a second perspective view thereof;

FIG. 3 is a bottom view of thereof;

FIG. 4 is a top view thereof;

FIG. 5 is a front view thereof;

FIG. 6 is a rear view thereof;

FIG. 7 is a right side view thereof; and,

FIG. 8 is a left side view thereof.

The broken lines in the drawings illustrate portions of the brake adjuster that form no part of the claimed design.

1 Claim, 6 Drawing Sheets(56)
